UNITED STATES PATENT OFFICE.

ROBERT B. EASTON, OF PAWTUCKET, RHODE ISLAND, ASSIGNOR TO EASTON AND BURNHAM MACHINE COMPANY, OF PAWTUCKET, RHODE ISLAND.

EXPANDING MANDREL FOR CONE-WINDERS.

SPECIFICATION forming part of Letters Patent No. 777,780, dated December 20, 1904.

Application filed February 23, 1904. Serial No. 194,952.

To all whom it may concern:

Be it known that I, ROBERT B. EASTON, a citizen of the United States, residing at Pawtucket, in the State of Rhode Island, have 5 invented a new and useful Improvement in Expanding Mandrels for Cone-Winders, of which the following is a specification.

The nature of my invention consists in the improved construction of an expanding mandrel whereby the cone may be readily attached and removed and firmly held in position while the thread or yarn is being wound thereon.

In the accompanying drawings, Figure 1 represents a longitudinal section showing the 15 mandrel with the cone attached thereto. Fig. 2 represents a side view of the mandrel without the cone. Fig. 3 represents an outer side view of the connected segments of the expanding head of the mandrel. Fig. 4 represents 20 a section of the same, taken in the line 4 4 of Fig. 3. Fig. 5 represents the outer side view of one of the segments of the expanding head removed from the other segment. Fig. 6 represents an inner side view of the segments of 25 the expanding head. Fig. 7 represents an edge view of the same. Fig. 8 represents a side view in which the segments of the expanding head are not connected together. Fig. 9 represents an end view of the mandrel shown 30 in Fig. 8.

In the drawings, A represents the arbor, to which the expanding head B is attached by means of the inclined flat springs C C, the inner ends *a a* of the said springs being secured 35 to the opposite sides of the arbor A by means of the rivet *b*. The expanding head B is formed of two semicircular segments *c* and *d*, the connecting ears *e* and *e'* of which are loosely secured to each other by means of the slots

40 *f f*, made in the ears *e e* of the segment *c*, and the screws *g g*, which are secured into the ears *e' e'* of the opposite segment *d*, the said ears being made to overlap each other, as shown in Figs. 4 and 7. The semicircular segments 45 *c* and *d* are provided at their inner sides with a projecting flange *h*, to which the spring *C* is secured by means of the rivet *i*, the outer end of which is prolonged beyond the side of

the segment to form the spur *j*, which by engagement with the inner surface of the cone 50 D serves to hold the cone firmly upon the mandrel, the outer surface of the segment also engaging with the inner surface of the cone.

The semicircular segments *c* and *d* are forced inward toward each other by the action of the 55 springs C C and are carried outward against the action of the said springs by means of the conical surface *k* of the nut E, which is held upon the arbor A by means of the screw-thread *l*, and by screwing the nut E back and 60 forth upon the arbor A the head A may be either contracted or expanded, as desired, for either attaching or removing the cone D. The forward end of the arbor A is provided with the conical surface *m*, adapted to fit the inner 65 surface of the small end of the cone. The nut E is preferably provided with a knurled flange *n*, by means of which it may be turned to either secure or release the cone D, the backward unscrewing movement of the nut serving 70 to release the cone for its ready removal from the mandrel and the reverse screwing-up movement of the nut serving to force the semicircular segments *c* and *d* outward against the reverse inward action of the springs to 75 hold the cone securely. The segments instead of being connected together by means of the slots *f* and screws *g* may be made separate and disconnected from each other in carrying out my invention, as shown by the segments 80 *c' c'* and *d' d'* in Figs. 8 and 9.

The expanding head B should properly form a true circle when in its extreme expanded condition, and its outer surface *o* is made conical to properly fit the inner conical surface of 85 the cone.

I claim as my invention—

1. In an expanding mandrel, the combination of the arbor, the inwardly-acting springs attached to the arbor, and the segments attached to the springs, with the conical nut for causing the outward movement of the segments, substantially as described.

2. In an expanding mandrel, the combination of the arbor, the inwardly-acting springs attached to the arbor, and the segments loosely

connected with each other and attached to the springs, with the conical nut for causing the outward movement of the expandible head, formed by the loosely-connected segments, substantially as described.

3. In an expanding mandrel, the combination of the arbor provided with a conical surface adapted to fit the smaller end of the cone, the inwardly-acting springs secured to the

arbor, and the conically-formed segments attached to the springs, with the conical nut for forcing the segments outward against the inward action of the springs, substantially as described. 10
